UNITED STATES PATENT OFFICE.

LOUIS ROTHSCHILD, OF NEW HAVEN, CONNECTICUT.

IMPROVEMENT IN APPARATUS FOR SPONGING CLOTH.

Specification forming part of Letters Patent No. 42,406, dated April 19, 1864.

To all whom it may concern:

Be it known that I, LOUIS ROTHSCHILD, of the city and county of New Haven, in the State of Connecticut, have invented a new and useful Improvement in Apparatus for Sponging and Shrinking all Kinds of Cloth Used by Tailors; and I do hereby declare that the following is a full, clear, and exact description of the construction, character, and operation of the same, reference being had to the accompanying drawings, which make part of this specification, in which—

Figure 1 is a perspective view of the whole apparatus. Fig. 2 is a perspective view of the boiler when the cylinder is removed. Fig. 3 is a perspective view of the cylinder when mounted in bearings for rolling on or taking off the cloth.

My improvement consists in the use of a perforated cylinder, made of sheet-metal and covered with woolen cloth, onto which I roll or wind the cloth to be sponged or shrunk in a close roll and cover it with cotton flannel and canvas, or either of them, to keep the air from the cloth being sponged or shrunk, and then mount it vertically on a suitable boiler, so that when steam is generated in the boiler it will pass into the central part of the cylinder, whence it will escape through the perforations in its surface and saturate and sponge or shrink the cloth, leaving its luster unimpaired.

I make the boiler of sheet metal, or any other suitable material, in the ordinary form of boilers to be used on a stove or furnace, and such as would be suitable for furnishing hot water for ordinary purposes in a tailor's shop, where the hot water can be drawn out by a faucet, substantially as shown at B, Figs. 1 and 2, except that I fit on a conical-shaped top, p, with an orifice or aperture, n, to admit the steam into the central part of the cylinder, and a circular vertical flange, e, onto or into which the lower end of the cylinder A is to be fitted steam tight, all as shown in Fig. 2. I fill this boiler with water and set it on the stove or furnace, as for common use, to furnish hot water.

I make the cylinder A, Figs. 1 and 3, of sheet copper, zinc, or any other suitable material, about thirty-two inches in length and from six to eight inches in diameter, (so as to be suitable and convenient for rolling or wind-

ing on a piece of broadcloth,) and I perforate its surface, as shown at a, &c., Fig. 1. These perforations should not extend entirely to the ends of the cylinder, but about in the proportions shown in Fig. 1, and they should occupy about one third of the whole convex surface. I make the upper end entirely closed, and I fit a suitable journal to it, as shown at b, Figs. 1 and 3, and I make the lower end open, so as to be readily fitted steam-tight onto or into the vertical flange e, Fig. 2, as indicated in Fig. 1, so that the cylinder will stand vertical; and a cap may be screwed onto this lower end, as indicated at d, Fig. 3, (and the female thread shown at e, Fig. 1,) which cap is fitted with a journal, as shown at g, Fig. 3, or the journal and cap may be fitted by any other convenient means. At each end of this cylinder should be fitted a flange, as h and k, Figs. 1 and 3, to project equal to the thickness of the cloth on the cylinder, but this is not essential. I cover this cylinder for its whole length with pilot-cloth, or other woolen cloth, to equal thickness, so that the steam shall never strike directly on the piece of cloth which is being sponged or shrunk. To wind on the cloth, I place this cylinder horizontally with its journal b and g resting in suitable bearings, as l, and place a crank, as m, on the end of the journal b, when all is ready to wind the piece of cloth onto the cylinder, all as shown in Fig. 3. I lay the piece of cloth to be sponged or shrunk, as C, on a table or bench, and attach one end of the piece to the cloth covering of the cylinder by sewing or otherwise; and by the use of the crank m I wind the whole piece upon the cylinder and secure the end by sewing or otherwise, using the hands, friction-rollers, or any other suitable means to guide and give the necessary tension to the cloth to cause it to be wound or rolled true and tolerably close. I then cover the roll with cotton-flannel and that with canvas, though either of them alone may answer. I then remove the cap d from the lower end of the cylinder and place the cylinder vertically on the boiler B, as shown in Fig. 1, having previously set the filled boiler in its place on the stove or furnace.

When steam is generated in the boiler B, it will pass up through the aperture n in the cone p, into the central part of the cylinder A, when it will fill the whole cylinder and be forced through the perforations into the cloth,

which will condense the steam and absorb the water until the whole roll of cloth is saturated, so as to be what is technically called "sponged" or shrunk. When this is completed, it will be indicated by the water showing itself like perspiration on the outer covering or canvas, when the cylinder should be taken from the boiler and placed with its journals in their bearing, as in Fig. 3, when the cloth may be unrolled by hand and laid in folds on the table, all as shown in Fig. 3.

The cylinder A may be attached to the boiler B by any other convenient means—as by passing the steam through the hollow journal g, extended into the cylinder, so as to deliver it in the central part, but always observing to place the cylinder vertical, so as to equalize the effect of the steam, &c.

Any quantity or kind of cloth may be sponged or shrunk at one time, from a single pattern to a whole piece, or more; and a coat pattern, with its buckram, canvas, padding, &c., and a pattern for pantaloons and vest, &c., may all be sponged or shrunk at the same time, being rolled on together.

The advantages of my improvement consist in the trifling expense, as every tailor needs a stove or furnace to heat his irons and a

boiler to furnish him with hot water, so that the cylinder is, substantially, the only addition, and in that the sponging or shrinking, even of a few yards, is effected in less time and with less labor than it could be done by hand, and in that by this method of sponging the whole of the luster of the best finished cloth is preserved.

I am aware that high steam has been used in perforated cylinders, when placed horizontal and kept constantly revolving, for the purpose of producing a gloss or luster while finishing the cloth; but I do not claim this, as my invention consists of the cheap and simple apparatus which every tailor may have in his shop; but

What I claim as my invention, and desire to secure by Letters Patent, is—

The use of a perforated and covered cylinder, standing vertically and stationary, in combination with a boiler, for the purpose of sponging and shrinking cloth, when the whole is constructed, combined, and used substantially as herein described.

L. ROTHSCHILD.
